UNITED STATES PATENT OFFICE

JESSE G. KING, OF DAYTON, OHIO, ASSIGNOR, BY MESNE ASSIGNMENTS, TO FRIGIDAIRE CORPORATION, A CORPORATION OF DELAWARE

REFRIGERATING APPARATUS

Application filed November 30, 1927. Serial No. 236,721.

This invention relates to improvements in refrigerating apparatus and more particularly the refrigerating elements used in connection with the production of cold in 5 mechanically refrigerated cabinets.

One of the objects of the present invention is to provide a relatively long compact and narrow evaporator of the flooded type which, although utilizing only a small quantity of refrigerant, provides a relatively long 10 horizontally disposed and large heat absorbing section. In carrying out this object I provide an elongated finned section forming the greater part of the length of the evaporator and the greater part of the metallic heat absorbing surface of the evaporator and I cool this long large finned section by long slender and horizontally disposed refrigerant conveying tubes.

20 The invention also contemplated providing a refrigerating means which is constructed and arranged to compensate for such heat losses which are greater in some parts of the cabinet than in other parts and 25 particularly those occurring through the end walls of the cabinet.

It is another object of the invention to provide an improved compact, narrow and long refrigerating unit or element which 30 may be mounted in display counters or the like such as those used in stores and which will not obstruct vision when positioned therein.

A further object of the invention is to provide 35 an improved refrigerating means which in combination with the structure of the display counter will secure efficient circulation of the cooling air within said display counter.

40 Further objects and advantages of the present invention will be apparent from the following description, reference being had to the accompanying drawings, wherein a preferred form of the present invention is 45 clearly shown.

In the drawings

Fig. 1 shows a side view of the improved refrigerating element of the invention;

49 Fig. 2 illustrates a top view of the same

with the header and ducts shown in broken separated relation;

Fig. 3 is a side view similar to Fig. 1 but showing details of the ducts and fins.

Fig. 4 represents an end view of the element looking longitudinally toward the header.

Fig. 5 is a side sectional view of a display case refrigerator equipped with the improved refrigerating element of the invention, and

Fig. 6 is an end sectional view of Fig. 5.

Referring in detail to the drawings the refrigerating element comprises a header 10 shown complete in Fig. 1 but in cut style in Figs. 2 and 3 which serves as a container for holding a refrigerating medium which may for example be liquid sulphur dioxide. This header serves to distribute the refrigerant to pipes or ducts hereinafter described. 70 The refrigerating medium is led into the header by a pipe 11 and is conducted away therefrom above the liquid level in the header by a pipe 12. A suitable float valve 13 shown diagrammatically in Fig. 1 is used 75 to control the flow of refrigerant to the header and adapted to maintain a constant level of liquid in the header.

A series of heat transfer means herein shown as refrigerant circulating ducts or 80 tubes which are formed of a plurality of loops of pipe, are connected to the header in parallel circuit relation as shown in the drawings, Figs. 2 and 3. These loops extend outwardly into the air cooled by the refrigerating element. The loops are constructed substantially as follows:

It will be observed in Fig. 2 that each loop extends longitudinally for a relatively short portion 14 outwardly from the longitudinal axis end of the header 10 whereas it is bent outwardly at the portion 15 and thereafter continues as a duct or tube 16 extending in the same longitudinal direction as the body of the header, the portion 16 being offset 95 with respect to the portion 14. The duct at its extremity remote from the header wall is looped around as at 17 and returns to the header wall as a straight duct which is not visible in the drawing of Fig. 2, since it lies 100

beneath a similar pipe or duct 18 belonging to another loop or duct 19 whose offset portion is not visible since it is in the same plane as the ducts 14, 15, 16. Similarly a duct 20 extends outwardly from the body of the header and in the same longitudinal direction thereof and whose bent portion 21 terminates in a duct attached to the same wall of the header but bent and laterally offset in 10 a manner analogous to the ducts 14, 15, 16 above mentioned. This return leg is not visible in Fig. 2 but is indicated by numerals 9, 8, 7 (see Fig. 3). Above the portions 7, 8, 9, there is attached to the header a portion comprising portions 22, 23, 24, bent and laterally offset as hereinbefore described, and whose straight portion 24 bends around at 25 to terminate in a duct similar to duct 20 of the other loop system but lying below the same. 15 20 A particular feature of the invention resides not only in bending and laterally offsetting the ducts as they leave the header but in criss-crossing the bent return portions 17, 19 and 25 of the respective loop ducts. This cross arrangement is more clearly seen in Fig. 4 in which 10 indicates the outline of the end of the header. 14 shows the portion of the duct loop which is connected with the header. 15 is the bent portion: 16 the longitudinally extending portion offset with respect to 14, and 17 is the bent-over extremity which enters the header at 26 after bending up as shown in Fig. 4, this point not being visible in Fig. 2.

35 In a similar manner the duct comprising portions 22, 23, 24, leads out at 22 from the header wall thereafter to bend at a point 23, to continue as portion 24 and to terminate after leaving the bent loop 25 and inclined upwardly as at 6 in Fig. 4 to continue as a straight tube or duct located below the duct 20 in Fig. 2. The duct 20 leaves the header in a somewhat similar manner except that it continues relatively straight until it 40 is bent around at 21 and returns as portions 9, 8, 7 located below duct portions 24, 23, 22 in Fig. 2 but not visible therein. A similar arrangement prevails with respect to duct 18 which leaves the header wall in longitudinally extending direction bending around at 45 portion 19 to terminate in portions 5, 4, 3 similar to and lying below 14, 15, 16 above described.

50 55 It will be observed that the round or bent-over portions 19 and 25 cross respectively the portions 21, and 17 (Fig. 4), these being the bent-over extremities of the duct loops.

The hereinbefore referred to "criss-cross" 60 arrangement of the extremities of the ducts obviates the necessity of making sharp bends or loops. It is apparent that ducts of the size used on elements of this type cannot be bent backward upon themselves without using a gradual loop.

This criss-cross arrangement also makes it possible to provide a long narrow and shallow refrigerating element whose duct system is confined within the transverse area of the end walls of the header, and which makes the element suitable for use in long confined spaces while still providing a large number of ducts or radiating surfaces.

70 75 It should be observed that the system of ducts longitudinally extending from the end of the header slants longitudinally downwardly with respect to the body of the header as shown for example in Fig. 1. This feature is also shown in Fig. 3 by the dotted lines of the ducts, the great length of the ducts with respect to the fins precluding the possibility of illustrating a connected view. If the ducts were connected to the end wall of the header so as to constitute a perfectly horizontal continuation or prolongation thereof, there is danger that refrigerant may become trapped in the looped end if the duct is tilted upwardly when the element is installed so as to bring the extremity above the liquid level in the header. By virtue of the present invention, however, even though the element is not placed in a perfectly horizontal position the ducts will possess sufficient tilt of their own to obviate such a contingency. Moreover, inclining the ducts provides for the natural upward flow of the gaseous refrigerant and facilitates the return of bubbles to the header.

80 85 90 95 100 The duct loops are provided with fins of good heat conducting material such as copper and these fins may consist for example of copper sheets 29 attached to the long horizontal runs of the loops in good thermal contact as by soldering. Tie bars 30 may be attached to the fins at intervals to produce 105 a solid structure and to prevent damage to the fins and ducts.

110 115 120 125 By this arrangement a long horizontal finned section provides the main heat absorbing surface of the evaporator and the long horizontal runs or tubes, although they contain only a small quantity of refrigerant, provide the major heat transfer section of the evaporator which is in contact with the refrigerant. Thus I have provided a long horizontal evaporator of the flooded type which utilizes only a small quantity of refrigerant and insures efficient refrigeration throughout the length of the evaporator. This long horizontal or spike-like evaporator is particularly adaptable for cooling long horizontal refrigerating compartments such as display cases of the type shown herein.

130 As previously explained the outer-lying ducts are laterally offset. This enables the fins to be spaced at such a distance that the frost will not readily build up across the fins and ducts so as to impede the circulation of air.

Figs. 5 and 6 illustrate the improved re-

frigerating element mounted in a refrigerator of the display case type. In such capacity its function is to replace the ice or the brine coils heretofore used for cooling and 5 circulating the air within the case.

In the display case illustrated the case itself comprises an elongated structure adapted for cooling food stuffs while maintaining the same on display. The case comprises 10 essentially a cabinet which may for example have a rectangular ground plan with a base 31 and a horizontal top 32. The walls of the case should be suitably heat insulated as by means of cork board 32'. The case may be 15 divided into an upper display compartment or chamber 33 and a lower, machine or storage compartment 34. The front wall which faces the customers is provided with glass panels preferably of the multiple air space 20 insulated type indicated by 35, while a similar construction may be provided at the rear with glass panelled doors 36 to admit access to the interior of the case and to permit inspection of such interior without necessitating opening of the doors. An impervious lining 37 may be provided in the interior of the case. The improved refrigerating elements hereinafter described are disposed in the interior of the cooling compartment 25 or display compartment of the case in the manner shown in Figs. 5 and 6. In the preferred embodiment of the invention a plurality of such units are used preferably with the header members 10 disposed near the end walls 38 of the display counter and with the refrigerant circulating ducts and fins 29 extending longitudinally toward each other so as to meet substantially 30 in the top center of the display case. This arrangement insures substantially even temperature throughout the chilling compartment. In as much as the headers constitute the coldest portions of the refrigerating means, the headers are placed adjacent the 35 end walls of the chilling chamber where, in the particular embodiment, the heat leakage is somewhat greater at these points than others and thereby substantially compensates for such heat leakage to maintain even temperature throughout the chilling chamber. 40

The refrigerating elements may be supported from the top of the display case by means of strap members 39 attached to the header 10 and to the fins 29. A drip pan 40 45 may be provided for each refrigerating element used so as to avoid dripping of moisture on the displayed food stuffs when the refrigerating element is being defrosted. Suitable refrigerant pipes 41 and 42 lead respectively to the header inlet and outlet 11 50 and 12 and these pipes are connected to a suitable type of refrigerating apparatus not shown but which may be located either in the machine compartment 34 of the case or 55 elsewhere.

While the form of embodiment of the invention as herein disclosed, constitutes a preferred form, it is to be understood that other forms might be adopted, all coming within the scope of the claims which follow. 70

What is claimed is as follows:

1. In a refrigerating display counter in combination an elongated food compartment, refrigerating means disposed in said compartment, said means comprising spaced header means adapted to contain a quantity of liquid refrigerant means, a plurality of ducts extending longitudinally of the cabinet and connected with said header means for circulating refrigerant medium throughout substantially the length of the cabinet, said ducts being disposed intermediate said header means. 75

2. In a refrigerated display counter in combination an elongated food compartment, refrigerating means in said compartment comprising an elongated header at each end of said compartment and adapted to contain a quantity of liquid refrigerant, refrigerant circulating ducts connected with the headers for receiving liquid refrigerant therefrom and longitudinally extending away from said headers and towards the center of said compartment, and fins on said ducts. 80

3. Refrigerating means for mechanically refrigerated cabinets comprising a header 95 adapted to contain a quantity of volatile liquid refrigerant and a plurality of duct loops having the ends thereof connected with an end wall of said header and below the liquid level therein, and means within the header for maintaining a predetermined quantity of liquid refrigerant therein. 100

4. Refrigerating means for elongated mechanically refrigerated cabinets comprising header means, duct loops extending therefrom, each duct comprising a pipe loop, each pipe loop emerging from an end wall of the header, extending therefrom for a short distance, then being offset outwardly and continuing in the same longitudinal direction 105 for a substantial distance, being bent around at its extremity and returning in a similar manner to a lower point on the same end wall of said header to form a circulatory duct loop, the bent-over extremities of the ducts 110 being arranged to cross each other. 115

5. Refrigerating means for elongated mechanically refrigerated cabinets comprising a header adapted to contain a quantity of liquid refrigerant, conduit means extending 120 from the header for cooling a space disposed horizontally of the header, said conduit means including a duct portion connected with the header below the normal liquid refrigerant level in the header and sloping downwardly through a substantial portion of its length, another portion connected with the header and disposed substantially parallel with the first portion but on a higher plane, and a loop connecting the portions. 125 130

6. Refrigerating means for elongated mechanically refrigerated cabinets comprising a header adapted to contain a quantity of liquid refrigerant, conduit means extending
5 from the header for cooling a space disposed horizontally of the header, said conduit means including a duct portion connected with the header below the normal liquid refrigerant level in the header and sloping
10 downwardly through a substantial portion of its length, another portion connected with the header and disposed substantially parallel with the first portion but on a higher plane, and a loop
15 connecting the portions.
7. A horizontally elongated spike-like evaporator disposed in the path of air for directly cooling the air, comprising a finned section forming the greater part of the horizontal length of the evaporator and the greater part of the metallic heat absorbing portion of the evaporator, said finned section including a compact group of long slender and horizontally disposed refrigerant conveying
20 tubes forming the major heat transfer section of the evaporator contacting with the refrigerant, some of said tubes being arranged on a higher plane than others, said finned section also including a plurality of
25 vertically extending fins each of said fins being intimately connected with a lower and an upper tube, and a header containing a quantity of volatile liquid refrigerant, said upper and lower tubes being each connected
30 with a vertically extending wall of the header in fluid exchange relationship with the interior of said header.
- 35 In testimony whereof I hereto affix my signature.
